UNITED STATES PATENT OFFICE

144,452

DESIGN FOR A ROOM COOLER OF THE WINDOW TYPE

Henry Dreyfuss, New York, N. Y., assignor to
Carrier Corporation, Syracuse, N. Y., a corpora-
tion of Delaware

Application May 3, 1945, Serial No. 119,369

Term of patent 14 years

(Cl. D62—4)

To all whom it may concern:

Be it known that I, Henry Dreyfuss, a citizen
of the United States, residing at New York, New
York County, State of New York, have invented
a new, original, and ornamental Design for a
Room Cooler of the Window Type, of which the
following is a specification, reference being had
to the accompanying drawing forming part
thereof.

Figure 1 is a perspective view taken from the
end that faces in a room of a room cooler of the
window type, embodying my new design; and

Figure 2 is a perspective view thereof taken
from the end that extends out of the window.

I claim:

The ornamental design for a room cooler of
the window type, substantially as shown.

HENRY DREYFUSS.
